UNITED STATES PATENT OFFICE.

JAMES E. MAYNADIER, OF TAUNTON, ASSIGNOR TO THE BUSELL TRIMMER COMPANY, OF BOSTON, MASSACHUSETTS.

ROTARY CUTTER.

SPECIFICATION forming part of Letters Patent No. 380,338, dated April 3, 1888.

Application filed January 23, 1884. Serial No. 118,491. (No model.)

To all whom it may concern:

Be it known that I, JAMES E. MAYNADIER, of Taunton, in the county of Bristol and State of Massachusetts, have invented an Improvement in Rotary Cutters, of which the following is a specification, reference being had to the accompanying drawings.

Figure 1 is a section through the axis of the cutter, and Figs. 2 and 3 are cross-sections on line $\alpha\alpha$ of Fig. 1, the first looking to the left and the other looking to the right, illustrating one form of cutter embodying my invention; and Fig. 4 is a perspective view of part of the guard, which is the main feature of my invention.

In rotary cutters as now used for trimming sole-edges the office of the guard, which is to prevent the teeth of the cutter from taking too thick a chip—that is, to prevent too much "rankness"—is performed by the outer end of each tooth.

My invention is a novel rotary cutter made up of a hub having a series of cutting-teeth integral with it, and another hub having a series of integral guard-teeth, one hub receiving the other, so that the guard and cutting teeth

are brought into and locked in proper relation to each other.

In the drawings, b is a hub having a series of integral guard-teeth, and f is a hub having a series of integral cutting-teeth, d . The hub f has a lateral annular groove to receive hub b , which is slid into the groove, (see Fig. 1,) so that the guard-teeth a lie between the cutting-teeth d , as plainly shown in the drawings. Hub b is secured to hub f by a set-screw, i , to prevent the guard from working laterally out of the cutter. The rotary cutter thus formed is mounted on shaft h , the screw h' preferably holding the rand-guide g in place and the cutter upon the shaft in the usual way.

What I claim as my invention is—

The rotary cutter consisting of hub f , having integral teeth d , in combination with a guard consisting of hub b , having integral teeth a , the two hubs f and b fitting together, so that the guard-teeth a alternate with the cutting-teeth d , substantially as and for the purpose set forth.

J. E. MAYNADIER.
